WILLIAM B. FULTON, OF MIDDLETOWN, OHIO.

STEAM-PRESSURE-REGULATING MECHANISM.

1,414,506.

Specification of Letters Patent.

Patented May 2, 1922.

Application filed May 21, 1921. Serial No. 471,362.

To all whom it may concern:

Be it known that I, WILLIAM B. FULTON, a citizen of the United States, residing at Middletown, in the county of Butler and 5 State of Ohio, have invented certain new and useful Improvements in Steam-Pressure-Regulating Mechanism, of which the following is a specification, reference being had therein to the accompanying drawing.

10 This invention relates to steam pressure-regulating mechanism for use in connection with steam paper driers.

In the art of paper making there is used what is known as a paper drier—an arrangement of hollow cylinders over which the paper is passed for the purpose of drying it. 15 These cylinders are so mounted and equipped that steam may be introduced into them from a boiler. The several cylinders constitute a 20 unit, all having a common connection with the boiler. The supply of steam to the point of distribution among the cylinders is controlled by a valve. The steam which gathers at this point of distribution is permitted to 25 gradually exhaust when its pressure, and therefore the intensity of the heat, is too great. Automatic mechanism is employed for controlling these valves, both the inlet and the exhaust valve. But in practice this 30 mechanism has not been under the control of an operator, with the consequence that the exhaust valve will often remain open too long. This reduces the pressure of steam too 35 much and chills the drying rollers, which retards or prevents the drying of the paper, so that all of the paper passing over the drying rolls during such an interval is insufficiently dried, if really dried at all.

It is to overcome these practical difficulties 40 that my invention is designed. I purpose to put within the control of the attendant the steam which in the system described is employed to operate the piston which, in turn, is designed to open the exhaust valve, so that 45 when he observes that the exhaust valve is about to remain open too long he can instantly relieve this piston of the pressure of steam which is then acting to move the piston too far with the tendency to open the exhaust 50 valve too wide and to keep it open too long.

By relieving this piston of the effect or continued effect of this steam he can either cause the exhaust valve to stand at the then degree to which it is open or to return to its 55 seat and close.

Such is the object of my invention and

this I carry out and accomplish by the means and in the manner hereinafter stated.

The accompanying drawing shows a part of the apparatus in vertical section and a 60 part in elevation, the features embracing my improvements being shown at the left side of the cylinder illustrated in section.

I do not deem it necessary to illustrate the "drier", but it will be understood that an inlet valve 1 is in a pipe line between a steam supply or boiler and this drier. This valve comprises a casing 2, a valve seat 3, a valve proper 4 and its stem 5. In the drawing this valve now stands open and it will be understood that the steam is flowing through the valve casing from the supply to the drier.

Connected with the drier at some convenient place is a valve 6 comprising a casing 7, a seat 8, a valve proper 9 having a stem 10. 70 This valve is shown closed because the steam in the drier has not fluctuated or risen to a degree requiring it to be reduced by a partial exhaustion. In this situation things may be stated to be normal.

But there will come a time when the pressure in the drier will become excessive with a tendency to overheat the drying rolls and to injure the paper. When that condition is reached the thing to do is to close the inlet 85 valve 1 and open the exhaust valve 6. This is done by means of a lever 11 connected with the valve stems 5 and 10, the former through a slot 12 which will compensate for the arc movement of the lever. At one or the 90 other of the points 13, according to local conditions, a cable 14 is connected to the lever and extended thence over guide pulleys 15 and 16 to a piston rod 17 to which it is attached. This rod extends within a cylinder 95 18 and carries a piston 19 adapted to travel up and down in the cylinder—upward under the excess pressure of the steam in the drier and downward by its weight when the pressure of the steam is lessened, or, in the case 100 of my invention, when some of the steam is permitted to escape from the cylinder 18 at a point below the position the piston 19 may then occupy.

I have spoken of the lever 11 as connected 105 with the valve stems 5 and 10. This lever fulcrums on one or the other of these stems. When the descent of the piston 19 draws on the cable 14 the lever 11 fulcrums on the valve stem 10 and lifts on the valve stem 5. 110 It also fulcrums on the stem 10 until the reverse movement of the lever seats the valve

4. When the valve 4 is seated and a further movement of the lever takes place it then fulcrums on the stem 5 and lifts the stem 10 and unseats the valve 9. Thus the lever alternately fulcrums on the stems 5 and 10.

The weight 11^a aids in the descent movement of that end of the lever 11, and tends to keep the cable 14 taut when the lever 10 is fulcruming on the stem 10.

The weight 11^b aids in the descent of that end of the lever when it is fulcruming on the stem 5. These weights are not essential but add somewhat to the smoothness of 15 the operation.

A steam pipe 20 extends from the drier to the cylinder 18 and acts on a valve 21 comprising a casing 22, a seat 23 and a valve proper 24 having a stem 25 which acts 20 against a balance beam 26 pivoted at 27 to a standard 28 and having an adjustable weight 29.

This weight is set to a position that will cause the lever 26 to resist the pressure on 25 the valve until that pressure exceeds what is desired, the lever having a scale in pounds, as shown, so as to determine where to set the weight. When the pressure on the valve 24 is sufficient to tilt the lever to the dotted 30 position, then the operator will understand that the piston 19 is climbing too high and opening the exhaust valve 9 too wide, or keeping it open too long, a condition which if unchecked would soon result in such a 35 delivery of steam from the drier as would reduce the temperature of the rolls too much.

Therefore, to check the further rise of the piston 19 and opening of the exhaust valve 9 the operator will open that port of the 40 series of ports 30 which is then beneath the more or less elevated piston 19. Such port is opened by operating the appropriate one of the several screw-threaded valve stems 31. The ports 30 lead into a chamber 32 45 whence the steam admitted to it by the opening of one or more of the ports 30 through the valve stems 31 will escape through the pipe 33.

In this way the rise of the piston 19 will 50 be checked and it will either partially or wholly return to its lower position and in doing so partly or wholly close the exhaust valve 9 and thus reduce or stop the exhaust of steam from the drier. And this escape

of the steam from the cylinder 18 will also 55 relieve the valve 24 and cause it to be reseated by the weight on the lever 26.

It will be observed that the ports 30 and their valve stems are distributed along much of the length of the cylinder 18 so that as 60 the piston rises from point to point there will be a port and valve immediately under the piston for the discharge of the surplus steam irrespective of how much water from condensation may happen to be in the chamber 32 if for any reason the pipe 33 has not had time to drain it all off.

A steam escape port 34 is formed in the wall of the cylinder 18 to permit of the escape of such steam as may press past the 70 packing between the cylinder and the piston.

Having thus fully described my invention, what I claim as new and desire to secure by Letters Patent, is:—

1. In an apparatus of the class described, 75 the combination, with a steam inlet valve, a steam outlet valve, and a lever to which they are connected, of a cylinder, a piston therein, its piston rod, a connection between the rod and said lever, a steam pipe connected with said cylinder beneath said piston through which steam may enter to actuate the piston and one or more valve ports and stems in the cylinder wall adapted to permit the escape of steam at points on the pres- 80 side of the piston.

2. In an apparatus of the class described, 85 the combination, with an inlet valve, an exhaust valve, stems on said valves, a lever connected to the stems of said valves, such lever being adapted to open the one and close the other valve when unrestrained, of a piston rod connected with said lever, a piston thereon, a cylinder containing said piston, a steam pipe to introduce steam into the 90 cylinder to act on the piston to cause the piston to rise and permit the lever to rock to cause the inlet valve to close and the exhaust valve to open, means to indicate an excess of pressure in said steam pipe and indicate 95 the necessity for opening of the exhaust valve, and one or more valve ports and stems to permit the escape of steam on the pressure side of said piston.

In testimony whereof I affix my signature. 100

WILLIAM B. FULTON.
